UNITED STATES PATENT OFFICE

2,449,187

PROJECTING APPARATUS

George C. Walters, Rocky River, Ohio

Application December 6, 1944, Serial No. 566,941

5 Claims. (Cl. 124—13)

1

The purpose of this invention has been to provide a simple, inexpensive amusement device for the entertainment of children primarily, though the invention may be used by older people as well and considerable fun derived therefrom.

A further special object of the invention has been to provide a projecting type of amusement device, simple in its construction, and which may be, therefore, manufactured at a relatively low cost so as to be produced in large volume.

Still another object of the invention has been to provide a projecting toy or amusement device of the class described which may be readily manufactured from paper or cardboard stock, and which, by very simple operation thereof, may project a projectile a considerable distance and with a greater or less amount of accuracy in reference to hitting a suitable target.

Still another object of the invention has been to so design my projecting device that by varying manipulation of the projectile member and a suitable plunger member working in conjunction therewith, the projectile may be fired, so to speak, with varying velocity, and to varying distances at which a target may be located.

With the foregoing objects in view I have illustrated a preferred embodiment of my invention in the accompanying drawings, in which:

Figure 1 is a side elevation of the projecting device or toy, with the parts arranged preliminary to their movement for effecting projection of the projectile member.

Figure 2 is a view similar to Figure 1, in which, however, it is seen that the projectile member has left or been projected from the plunger member working in the handle or barrel of the device.

Figure 3 is a side elevation view showing the device of the invention with the parts telescoped into the position assumed when not in use, or suitable in packing of the device in a container using a minimum amount of shipping space.

Figure 4 is a view in longitudinal sectional illustration with the parts in the positions in which they are shown in Figure 3.

Figure 5 is a transverse sectional view through the device taken about on the line 5—5 of Figure 4.

Figure 6 is a side view showing a modified form of projectile member.

Figure 7 is a view similar to Figure 6, illustrating still another form of projectile member that may be employed as a part of my inventive device.

Referring to the drawings and describing my

2

device in detail, I show in Figures 1 to 4 inclusive that my invention is comprised, primarily, of three parts, namely, a handle or barrel member 1, a hollow plunger member 2, and a projectile member 3. The barrel member 1 is closed at one end thereof by means of a plug or member 4, and the hollow plunger member 2 is designed to telescope therein and snugly fit into the barrel or handle member 1. The member 2 likewise is capable of free sliding movement in its telescopic connection with the barrel member 1.

In regard to the projectile member 3, the same comprises a head or body portion which may be rounded, or otherwise contoured, depending upon the shape which it is desired to give the projectile member. Said projectile member 3 is provided with a hollow shank portion 5. The projectile member 3, in reference to the form of the shank portion 5 is constructed so that the shank 5 fits snugly and telescopes within the outer end of the plunger 2. The head of the projectile member 3 has an annular shoulder that abuts with the other extremity of the plunger 2 when the projectile is fitted so that its shank 5 enters the plunger 2 to the fullest extent possible.

With the foregoing construction in mind, it is evident that the projectile member in conjunction with the plunger 2 forms a sort of piston operating along the barrel member 1.

Now when the device of my invention is used by being supported by the hands, the operator or child playing with the projecting device will preferably grasp the barrel member 1 in the left hand, and pull the plunger 2 outwardly previous to placing the projectile member 3 in position thereon. The projectile member 3 will then be applied to the outer end of plunger 2 acting as a closure therefor, so that the parts assume the positions similar to those illustrated in Figure 1. With the right hand grasping the projectile member 3 at about the point of the juncture of the projectile member 3 at its shoulder, with said plunger 2, the person operating the device will then force the plunger 2 and the projectile member 3 sharply inwardly toward the barrel member 1, the plunger 2 of course telescoping into the latter by such action. By maintaining a more or less firm gripping pressure on the members 2 and 3 at their juncture point or adjacent the annular shoulder of the projectile 3, the operator of the device can control the time of release of the projectile 3 acting under the compression of the air within the members 2 and 1 as the member 2 with the member 3 is

forced longitudinally of the member 1. Since the parts 2 and 1 snugly fit together, the projectile member 3 snugly fitting within the outer end of the plunger 2, a considerable amount of compression of the air in the parts 1 and 2 may be produced, and it has been found in practice that the projectile member 3 may be projected very considerable distances from the member 2 in the use of the device in the manner above described.

It will be noted from Figure 6 that I provide a modified form of projectile member 3a having the hollow shank portion 5a, and in this form the projectile member is pointed, and the parts described in reference to Figures 1 and 6 may all be made from paper stock or cardboard stock, and the members 3, 2, and 1 may be of round form in cross section, or they may be of rectangular or equivalent form so long as the telescopic fitting of the members 1, 2, and 3 together is preserved, using a snug sliding fit between the parts.

I have illustrated in Figure 7 another form of projectile member which comprises the head 3b, shank 5b, and rubber cup 3c. The projectile member of Figure 7 will operate much after the manner of rubber cup darts that are quite commonly used in amusement projecting apparatuses or devices of today. When the projectile member of Figure 7 is fired, the rubber cup 3c may strike a target board and will, by suction, affix itself to the board at the point of impingement contact.

While my invention is preferably made from paper or cardboard stock, I do not wish to be limited to such material because obviously the device could be constructed of wood, or from fiber, or even plastic compounds of many different kinds so commonly used today.

It will be apparent from the foregoing that my device provides an amusement article of high interest and one that may be employed in different ways for the projecting of a projectile toward a target or other object at some distance away.

Having thus described my invention, what I claim as new and desire to secure by Letters Patent of the United States, is:

1. A projecting device of the class described, comprising a barrel member closed at one end, a hollow plunger open at both ends and slideable snugly inwardly and outwardly of the barrel member at its opposite end, and a projectile member fitted to close the outer end of the hollow plunger member and to be projected therefrom by compression of air between the projectile member and the closed end of the barrel member incident to forcing the projectile member and plunger inwardly or toward the closed end of the barrel member.

2. A device of the class described comprising a pair of telescopically associated tubes, the outermost of which is closed at one end and the other of which is open at both ends, and a cap detachably mounted on the outer end of the inner tube in sealing relationship therewith, said cap being adapted to be disengaged and propelled from the inner tube by virtue of air pressure generated by telescoping the inner tube within the outer tube.

3. A projecting device as set forth in claim 1, in which the projectile member includes a shank portion adapted to fit snugly into the outer open end of the hollow plunger, and in which the plunger is long enough to project from the barrel member so that the projectile member may be grasped in forcing it and the plunger toward the closed end of the barrel member.

4. A projecting device of the class described, comprising a long tubular member closed at one end and open at its other end, a long tubular plunger member open at both ends and slideable telescopically in the long tubular member first mentioned at the open end of the latter, and a projectile member comprising a head formed with a shank fitting snugly into the outer open end of the tubular plunger member, said plunger member being long enough to project from the long tubular member first mentioned so that the projectile member may be grasped in forcing it and the plunger member toward the closed end of the barrel member.

5. A projecting device of the class described, comprising a barrel member closed at one end, an open ended plunger member slideable snugly in and out of the barrel member at its opposite end, and a projectile member fitted to close the outer end of the plunger member so that on forcing the plunger member inwardly the projectile member will be projected from the barrel member, said plunger member being long enough to project from the barrel member so that the projectile member may be grasped in forcing it and the plunger member toward the closed end of the barrel member.
